UNITED STATES PATENT OFFICE

VALENTIN LIND, OF BERLIN-CHARLOTTENBURG, GERMANY, ASSIGNOR TO GENERAL ELECTRIC COMPANY, A CORPORATION OF NEW YORK

CONTROL SYSTEM

Application filed January 29, 1929, Serial No. 335,780, and in Germany February 15, 1928.

My invention relates to systems of control for electric motors and more particularly to systems in which a load such as an electric elevator or a hoist is driven by the motor 5 along a definite pathway having a plurality of predetermined stopping points.

Heretofore, electric elevator systems have been known in which push buttons have been used for operating the control mechanism 10 for preselecting landings, to which it is desired to cause the car to travel; to start the car, and finally to cause the car to be stopped at the selected landing. The systems of the prior art while successful and operative entail certain disadvantages. Among the disadvantages are the large number of conductors that are required between the car and the control apparatus, which number 15 obviously becomes larger with an increasing number of landings. Another disadvantage of the systems of the prior art is that the control mechanism is complicated and involved.

My invention has for an object the simplification of systems of the above type and the provision of a system that will be free from the disadvantages of the prior art systems.

In carrying out my invention in one form, I provide an electric impulse sending dial switch on an electric motor driven elevator car for actuating suitable control mechanism to start the car and to stop it at a landing corresponding with the number of impulses sent through an electric circuit by the dial switch.

For a more complete understanding of my invention, reference should be made to the following specification in conjunction with the accompanying drawings in which Fig. 1 40 is a view in elevation of a dial switch used for sending electrical impulses to the control apparatus; Fig. 2 is a plan section of the dial switch; Fig. 3 is a cross section of the dial switch; Fig. 4 is a selector switch; Fig. 5 is a diagrammatic representation of my elevator control system; Figs. 6 and 7 are modifications of the system of Fig. 5.

Referring now to the drawings in Fig. 1, I have shown a dial switch of the type used on 50 automatic telephones. The face of the dial

comprises a front wall 1 of the switch casing, a stop 2 and a rotatable selector disk 3. The disk 3 is provided with a plurality of numbered holes which, when the switch is used in an elevator system, correspond with the 55 numbers of the landings.

The selector disk 3 is fixed on the shaft 4 to which a disk 5 is keyed inside the casing. The disk 5 carries at its periphery a spring pressed pawl 7 adapted to engage a ratchet 60 disk 8 which together with the notched disk 9 and the gear 10 is mounted on the hub 11 which in turn is rotatably mounted on the shaft 4. A wound spring 6 serves to bias the disk 5 to normal or rest position. A fan 65 wheel 12 which serves as a brake to limit the speed of the moving parts when in operation, is driven by the gear 10. The notched disk 9 engages the roller 13 which is mounted on the movable spring contact lever 14 which 70 carries a contact member 15 at its free extremity. In similar fashion a roller 17 mounted on the spring contact arm 18, which carries a contact member 19 at its free extremity, is adapted to be engaged by a pawl 16 carried 75 by the disk 5. The contact members 15 and 19 serve to close electric circuits when pressed against their respective stationary members in response to the movement of the notched disk 9. The operation of the dial switch is 80 as follows: The finger is placed in a numbered hole of the selection disk 3 corresponding with the landing to which it is desired to dispatch the elevator car and the selector disk 3 is pulled around in a clockwise direction until 85 the finger reaches the stop 2, and is then released. When the disk 3 is turned in a clockwise direction, the disk 5 is also turned, the wound spring 6 put under tension, and the pawl 7 slid inoperatively over the teeth of 90 the ratchet disk 8. After being released, the disk 3, shaft 4 and the disk 5 are moved in a counter-clockwise direction by the action of the spring 6. The pawl 7 engaging a tooth of the ratchet wheel 8, the hub 11 is also rotated in the counter-clockwise direction together with the notched disk 9 and the gear 95 wheel 10. The fan 12 is driven by the gear wheel 10 and the speed of the rotating parts is limited thereby. A reciprocating motion is 100

- imparted to the spring lever 14 by the motion of the notched disk 9 and an electric circuit is made and broken at the contact 15 each time the roller 13 is raised and lowered and 5 a number of electrical impulses is thus sent through the electrical circuit, which number corresponds with the number of the hole in which the finger was placed. On the return movement only, of the disk 5, the contact lever 10 18 is depressed once by the cooperation of the pawl 16 and the roller 17 shortly before the parts have attained their initial position so that the contact 19 at the end of each operation of the dial will send a single electrical 15 impulse through a circuit to a control device.

The mechanical construction of the selector switch is illustrated in Fig. 4. Bearings 20 and 21 are attached to a base plate 22. An insulated support 23 for the contact rails 25, 20 26 and 27 is also attached to the base plate 22. A shaft 28 is supported in the bearings 20 and 21 and carries the contact arms 29 and 30 on an insulating disk 31 and also the two ratchet wheels 32 and 33 adapted to be engaged by 25 the pawls 34 and 35 respectively, which are operated by the electromagnets 36 and 37 respectively. A return spring 38 engages the ratchet disk 33 mounted on the shaft 28 and is placed under tension by the rotation of the 30 shaft 28. Upon the release of the latter, a spring 38 returns it to its initial position. A hollow shaft 39 is loosely mounted on the shaft 28 and is turned in either direction either by the sprocket wheel 40, or by the 35 magnets 41 and 42 in conjunction with the pawl mechanisms 43 and 44. The sprocket wheel 40 can be driven by the winding drum through suitable reduction gearing. On the hollow shaft 39 an insulated third contact 40 arm 24 is fixed. Each of the contact rails 26 and 27 (which may be combined to form a single rail) consists of a plurality of single points. The corresponding points on each rail are conductively connected with each 45 other as shown and their number corresponds with the number of switch positions of the dial switch or with the number of landings to be traversed.

The contact rail 25 is shown as a single 50 arcuate shaped member. The magnet 36 serves as a "stepper" magnet for the shaft 28 and the contact arms 29 and 30. Each time its armature is attracted, it steps the ratchet disk 32, and the disk 32 is advanced 55 one tooth. The pawl mechanism 35 serves to retain the shaft 28 and the contact arms 29 and 30 in their respective positions for the time being. Upon energization of the magnet 37 the pawl 35 is withdrawn from engagement with disk 33 and the shaft 28 is returned to its initial position by the spring 38. The electrical connections of the parts are diagrammatically illustrated in Fig. 5 in which like reference numerals indicate like 60 parts in the figures previously described. In 65

addition a driving motor 45 is supplied from a suitable source of electric power 46. Control relays 47 and 48 are provided for controlling the closing of the reversing switch 49 for the desired direction of rotation of the motor. The control relays have auxiliary contacts 50 and 51 respectively for establishing self-holding circuits. A relay 52 also provided with auxiliary contacts 53, serves to energize the windings of the control relays 47 and 48 and a fourth relay 54 is provided for the dual purpose of controlling the operation of relay 52 and deenergizing the control relays 47 and 48 at the proper time. The contact 55 is mounted on the motor starter 56 (see Fig. 6) and serves to energize the releasing magnet 37 of the selector switch when the motor starter is in "off" position. Likewise the contact 63 is mounted on the motor starter 56 and is arranged to establish circuit connections for the coil of relay 52 and for the coil of the "stepper" magnet 36 during the dialing operation.

In the drawings, the car is at the fourth landing as indicated by the fact that the traveling contact 24 is standing on the fourth point of the selector switch. The apparatus being in normal or "rest" position, the other parts are all in the position shown in the drawings. Assuming that it is desired to cause the car to descend to the second landing, the finger is placed in the hole marked 2 on the selector disk 3 and pulled in a clockwise direction until the finger reaches the stop 2 and is then released. The disk 3 upon being released returns to initial position and as it returns, the notched disk 9 causes the contact member 15 to engage its stationary member twice thereby establishing and interrupting an electric circuit to the coil of the "stepper" magnet 36, thus delivering two current impulses to the "stepper" magnet which steps the contact arm 30 to the second point on the selector switch and the contact arm 29 to a corresponding position on the contact rail 25. The return of the dial switch to initial position closes the contact 19 momentarily energizing the coil of the control relay 48 over the following circuit: Positive conductor P, contact 19, lower contacts 58 of the relay 52, coil of control relay 48, lower contacts 59 of the relay 54, to negative conductor N. Relay 48 picks up establishing a self-holding circuit that may be traced from positive conductor P, contact arm 29, contact 25, auxiliary contacts 51 of relay 48, coil of relay 48, lower contacts 59 of relay 54 to negative conductor N. The control relay 48 in picking up also closes its main contacts 60 thereby energizing the coil 61 and closing the reversing switch 49 to establish correct connections to the armature of motor 45 for the "down" direction of travel and the coil 72 (see Fig. 6) of motor starter 56 is energized 65 in a well known manner to cut out starting 70 75 80 85 90 95 100 105 110 115 120 125 130 135 140 145 150 resistance in the armature circuit. The motor starts and the car descends. As the car descends the traveling contact 24 which is driven in response to the movement of the car, moves downwardly over the points of the selector switch until it makes contact with the second point and establishing a circuit from positive conductor P, contact arm 30, second point of selector switch, traveling contact 24, coil of relay 54 to negative conductor N. Relay 54 picks up and in so doing opens the energizing circuit of the control relay 48 with the result that the contacts of the reversing switch 49 are opened and the motor starter 56 returned to "off" position, the motor 45 stopped, and the car brought to rest at the second landing. The motor starter 56 in returning to "off" position closes the contact 55 to complete a circuit from the positive conductor P through contact arm 29, releasing coil 37 of the selector switch, contact 55, to the negative conductor N releasing the locking of shaft 28 and permitting it and the contact arms 29 and 30 to return to initial position under the influence of spring 38. When the contact arm 30 slides off the second point on the selector switch, the energizing coil circuit of relay 54 is broken and the relay falls back to its initial position.

The operation of the system for the "up" direction of travel is very similar to that for the "down" direction. Assuming again that the car is standing at the fourth landing and that it is now desired to send the car to the seventh landing, the operation will be as follows: Seven impulses will be sent to the stepper magnet 36 of the selector switch by the operation of the dial switch and the contact arm 30 will be stepped successively over the points of the selector switch until it reaches the seventh point. When the contact arm 30 reaches the fourth point on the selector switch (one which the traveling contact 24 is standing) and the contact arm 29 is also making contact with the contact rail 25, the coil of relay 54 will be energized as follows: from positive conductor P, contact arm 30, fourth point of selector switch, traveling contact 24, coil of relay 54 to negative conductor N. Relay 54 will then pick up closing upper contacts 62 and establishing a circuit through the energizing coil of relay 52 from positive conductor P through contact arm 29, contact 25, coil of relay 52, upper contacts 62 of relay 54, contact 63 on motor starter 56, to negative conductor N. The relay 52 then picks up closing auxiliary contacts 53 to establish a self-holding circuit and also closes the upper contacts 64. When the contact arm 30 leaves the fourth point of the selector switch, coil of relay 54 is deenergized and the relay drops back but relay 52 remains picked up. The dial switch in returning to initial position closes the contact 19 momentarily to complete a circuit through the wind-

ing of control relay 47 over a circuit that may readily be traced. The control relay 47 picks up establishing a self-holding circuit in a manner already described for relay 48. The control relay 47 in closing its main contacts 65, closes the reversing switch 49 for the reverse direction of travel and the motor 45 starts in the desired direction causing the car to ascend. The remaining switching operations take place in the manner described for the downward direction of travel.

In the modification shown in Fig. 6, contact rail 27 of the selector switch and its co-operating traveling contact arm 24 described in connection with Figs. 3, 4 and 5 are dispensed with. In their place the contacts 127 are arranged in the shaft and cooperate with the contact 124 mounted on the car. The contacts 127 are connected with the corresponding points of the contact rail 26 of the selector switch. In this figure the motor starter 56, on which the auxiliary contacts 55 and 63 are arranged, is also conventionally indicated and is set in action by means of the winding 72. The circuits and the reference numerals for the other elements are the same as in Fig. 5 so that the operation can be followed from the above description without any difficulty. A knife switch 66 is provided in the car for the purpose of enabling it to be stopped at any desired point in its travel.

Fig. 7 shows a further modified form of the connections in the car and in the selector switch. It will be observed that the right hand side of the connection is omitted since it is the same as Fig. 6. In order to avoid the bare contacts in the shaft illustrated in the modification of Fig. 6, cams 67 are mounted at intervals in the shaft and operate the switch 68 in the car by means of the cam follower 69. The cam follower 69 is a part of the switch 68 as conventionally illustrated in the drawings and the switch is mounted on the car so that the cam follower successively engages the cam 67 as the car traverses the shaft. In this modification the two contact arms 30 and 24 are arranged to make contact with the points of contact rail 26 of the selector switch, the first of which is rotated by the "stepper" magnet 36 and later by the rope pulley 70 which is driven from the winding drum in accordance with the movement of the car. The operation is substantially the same as that previously described for Figs. 5 and 6.

Suitable push buttons may be provided at each floor for calling the car to a desired floor when it is stopped at another floor. These push buttons control suitable switching mechanism for starting and stopping the motor, and the control circuits are so arranged that they are non-interfering, i. e., if a button at a floor has been pushed to call the car, and a button is subsequently depressed at another floor, the control circuits

which were set by pushing the first button will not be interfered with by the depression of the second button. Systems of this type are well known in the art and form no part 5 of the present invention.

It will be understood that the elevator car 71 is connected by cables to a suitable winding drum (not shown) and that the winding drum is driven by the motor 45 through suitable 10 driving connections (not shown). These connections form no part of the present invention and have been omitted for the purpose of simplifying the drawings.

Although I have principally described my 15 invention as applied to a system of control for electric elevators, I would have it understood that I do not intend that the invention should be limited thereto, since it is equally applicable to any system of electrical control 20 in which a movable load body is adapted to be driven between predetermined stopping points located at intervals along a definite path-way.

While I have explained and illustrated my 25 invention as embodied in concrete form and operating in a specific manner, in accordance with the provisions of the patent statutes, it should be understood that I do not limit my invention to the foregoing illustrations since 30 various modifications will readily suggest themselves to those skilled in the art without departing from the spirit of my invention or the scope of the annexed claims.

What I claim as new and desire to secure 35 by Letters Patent of the United States is:

1. The combination with an elevator car and an electric motor for driving said car, of a contact device, means responsive to operation of said contact device for controlling 40 said motor to stop said car at points determined by the number of times said device is operated, and car position responsive means for determining the direction of rotation of said motor.

2. In combination, means including a translating device for driving a load body along a constrained path, an impulse transmitting device, means responsive to operation of said transmitting device and the operation 45 of said translating device for controlling the latter to stop the load body at a predetermined stopping point determined by the number of times said transmitting device is operated, and means controlled by the position of said load body at the time said impulse device is operated for determining the direction of operation of said translating device.

3. In a control system, means including a 50 translating device for moving a load body along a constrained path, an impulse transmitting device, means responsive to the operation of said transmitting device and the movement of the load body for controlling 55 said translating device to stop said body at

predetermined stopping points determined by the number of times said transmitting device is operated, and means actuated by said stop control means for selectively determining the direction of operation of said translating device. 70

4. In a system for controlling the operation of electric elevators and the like, means including an electric motor for raising and lowering a car, means including an impulse transmitting device and an impulse receiving device operated thereby for controlling said motor to stop the car at a predetermined stopping point determined by the number of times said transmitting device is operated, and means controlled by the position of said car and actuated by said motor controlling means for determining the direction of rotation of said motor. 75 80

5. In an elevator system means including an electric motor for raising and lowering a car, an impulse transmitting device, an impulse receiving device operated thereby, means operable in response to operation of said receiving device and the movement of the car for controlling said motor to stop the car at predetermined landings determined by the number of times said transmitting device is operated, and means comprising an electro-responsive device controlled by the position of said car and actuated by said impulse receiving device for determining the direction of rotation of said motor. 85 90 95

6. In a system for controlling the operation of electric motors, an electric motor supplied from a source of power and arranged to drive a load body along a path having a plurality of stopping points, means for controlling the motor including a selector switch for preselecting one of the stopping points 100 105 at which the load body is to stop, a manually operated dial switch for sending a number of current impulses through an electric circuit for operating the selector switch to a predetermined position, a normally open electric circuit having a control relay for controlling the starting of the motor, a contact associated with the dial switch for momentarily closing the normally open circuit to operate the control relay to motor starting position, and a second relay actuated by said selector switch for determining the direction of rotation of said motor. 110 115

7. In a switching device for the control of electric motors adapted to drive a movable load along a path having a plurality of predetermined stopping points, a control relay for starting the motor in one direction, a second control relay for starting the motor in the opposite direction, a selector switch for preselecting one of the predetermined stopping points for the load, a manually operated dial switch for sending electrical impulses through a circuit to operate the selector switch to a predetermined position and means 120 125 130

- responsive to a condition of the selector switch for operating the control relay for the desired direction of rotation when the dial switch returns to normal position.
5. In switching apparatus for controlling the movement of electric motor driven elevator cars in a shaft having a plurality of landings, means for controlling the operation of the motor including a selector switch having a plurality of points corresponding with predetermined landings, a rotating "stepper" magnet for moving a switch arm to make contact with a desired point on the selector switch to preselect a desired landing for the car, and a manually operated dial switch for sending electrical impulses through an electric circuit to operate the rotating "stepper" magnet.
9. In switching apparatus for the controlling of the movement of an electric motor driven elevator car in a shaft provided with a plurality of landings, a relay for controlling travel of the car in the "up" direction, and a relay for controlling travel of the car in the "down" direction, a dial switch normally biased to rest but operable to a predetermined position to send a predetermined number of electrical impulses through an electric circuit, a selector switch having a plurality of points corresponding with the landings and a stepper magnet operable in response to the electrical impulses to move a switch arm to a desired point on the switch, means responsive to a condition of the selector switch for setting an open circuit to the control relay for the desired direction of travel, and contact means actuated by the dial switch when it returns to rest position to close the said open circuit to start the car in the desired direction.
10. In combination with an electric motor supplied from a source of power, a load body adapted to be driven by the electric motor along a definite path having a plurality of predetermined stopping points, means for controlling the operation of the motor including means for sending a predetermined number of electrical impulses through an electric circuit, a selector switch operable in response to the impulses to predetermine a stopping point for the load body, means operable by the impulse sending means to start the electric motor, reversing switch mechanism for said motor, and means responsive to operation of said selector switch for controlling said reversing switch mechanism.
11. In a system for the control of electric motors, a load body driven by the motor and adapted to be moved in either direction along a path having a plurality of definite stopping points, means for controlling the motor including switching means for sending a number of electrical impulses through an electric circuit, a selector switch operated in response to the electrical impulses for determining the stopping point for the load body, reversing switch mechanism for determining the direction of rotation of the motor, and means cooperating with the selector switch and the first named switching means for controlling said reversing switch mechanism to start the motor in the desired direction of rotation.
12. In a system for the control of electric motors, a load body, an electric motor operable in opposite directions of rotation to drive said load body in either direction along a path having a plurality of fixed stopping points, means for controlling the motor including switching means for sending a number of electrical impulses through a circuit, a selector switch operated to a desired operative position by the impulses for determining the stopping point for the load body, and means cooperating with the selector switch and the first named switching means for starting the motor in one of said directions of rotation and to stop the load body when it reaches the predetermined stopping point.
13. In a system for the control of electric motors, a load body driven by the motor and movable in either direction along a path having a plurality of definite stopping points, means for controlling the motor including a selector switch having a number of points equal to the number of stopping points, a relay for controlling the direction of rotation of the motor in one direction, a second relay for controlling the rotation of the motor in the reverse direction, a third relay normally at rest in one position to energize the first relay and operable to a second position to energize the second relay, a traveling contact controlled by the load body and adapted to be in electrical contact with the point on the selector switch corresponding with the stopping point at which the load body may be at rest, a dial switch for sending a number of electrical impulses through a circuit and stepping a movable contact arm to a desired point on the selector switch, a fourth relay for operating the third relay to its second position when the movable contact arm makes electrical contact with the said point on the selector switch during a stepping operation of said contact arm, and a contact on the dial switch adapted to cooperate with the third relay to establish circuit through the operating winding of the second relay to start the motor in the said reverse direction.
14. In a system for the control of electric elevators and the like; an elevator car adapted to be driven by an electric motor in a shaft having a plurality of landings, means for controlling the starting and stopping of the motor including means located in the car for sending a number of electrical impulses through an electric circuit, and means responsive to the electrical impulses for determining the stopping point for the load body, reversing switch mechanism for determining the direction of rotation of the motor, and means cooperating with the selector switch and the first named switching means for controlling said reversing switch mechanism to start the motor in the desired direction of rotation.

ing the landing to which the car is to be sent. 15. In a system for the control of electric elevators and the like, an elevator car adapted to be driven by an electric motor in a shaft having a plurality of landings, means for controlling the operation of the driving motor including a dial switch located in the car for sending a plurality of electrical impulses through an electric circuit, and a selector switch responsive to the electrical impulses for determining a landing for the car.

16. In a system for the control of electric elevators and the like, an elevator car adapted to be driven in either direction in a shaft having a plurality of landings by an electric motor, means for controlling the operation of the motor including means located in the car for sending a number of electrical impulses through an electric circuit, means responsive to the electrical impulses for determining the landing for the car and means responsive to the conjoint operation of the first named means and the second named means for determining the correct direction of rotation for the motor to drive the car to the desired landing.

17. In a system for the control of electric elevators and the like, an elevator car adapted to be driven in either direction in a shaft having a plurality of landings by an electric motor, means for controlling the operation of the motor including a manually operated dial switch located in the car for sending a number of electrical impulses through an electric circuit, a landing selector switch responsive to the electrical impulses for determining a landing for the car, means responsive to the conjoint action of the dial switch and the landing selector switch for starting the motor in the desired direction, and means responsive to the conjoint action of the landing selector switch and the travel of the car for stopping the car at the selected landing.

45 18. In a system of control for electric elevators and the like, an elevator car adapted to be driven by an electric motor in either direction in a shaft having a plurality of landings, means for controlling the operation of the motor including a landing selector switch having a plurality of points, each point corresponding with one of the landings, a manually operated dial switch located in the car for sending a number of electrical impulses through an electric circuit to operate the selector switch to a desired point, means responsive to the conjoint action of the dial switch and the selector switch for starting the motor in the desired direction of rotation; and means including a travelling contact adapted to make successive contact with the points on the selector switch in response to the motion of the car for stopping the motor when the car is at the desired landing.

19. In a system of control for electric elevators and the like, an elevator car adapted to be driven by an electric motor in either direction in a shaft having a plurality of landings, means for controlling the operation of the motor including a landing selector switch having a plurality of points, each point corresponding with one of the landings, a manually operated dial switch located in the car for sending a number of electrical impulses through an electric circuit to operate the selector switch to a point corresponding with the desired landing, means responsive to the conjoint action of the dial switch and the selector switch for starting the motor in the correct direction of rotation for the desired direction of travel of the car, and means including a travelling contact, the latter travelling through a space corresponding with the travel of the car to make successive electrical connection with the points on the selector switch and to establish an electrical circuit through a relay to cause said relay to operate and de-energize the motor starting means when the travelling contact makes contact with the point to which the selector switch has been operated.

In witness whereof I have hereunto set my hand this 10th day of January, 1929.

VALENTIN LIND.
